BODY FOR CARS

Raymond S. Humburch, Rochester, N. Y.

Application October 5, 1932, Serial No. 636,346

7 Claims. (Cl. 105—404)

The object of this invention is to provide a new and improved body for an automobile truck or a railroad car.

Another object of the invention is to provide 5 new and improved ventilating apparatus for such a body.

Another object of the invention is to provide a construction for the car body which readily permits the removal of a side, or the roof, of the 10 car.

Another object of the invention is to provide a metal floor for the car attached to the under-frame in a way that makes it unnecessary to put holes in the metal floor.

15 These and other objects of the invention will be illustrated in the drawings, described in the specification, and pointed out in the claims at the end thereof.

In the drawings:

20 Figure 1 is a sectional elevation, partly broken away, showing one end of the car viewed from the interior.

Figure 2 is a vertical section through the end of the car showing the ice bunker, the section being partly broken away and being taken on the line 2x—2x of Figure 1.

Figure 3 is a horizontal section on the line 3x—3x of Figure 2.

Figure 4 is a vertical transverse section, partly broken away, through the floor, side and roof of the car.

Figure 5 is a horizontal section on the line 5x—5x of Figure 4.

Figure 6 is a longitudinal section through the car showing the scheme of ventilation diagrammatically.

Figure 7 is a horizontal section through the side of the car, partly broken away, the section being taken on the line 7x—7x of Figure 4.

40 Figure 8 is a vertical section through the roof of the car, the section being partly broken away and taken on the line 8x—8x of Figure 4.

Figure 9 is a horizontal section through the end of the car, the section being partly broken away and taken on the line 9x—9x of Figure 2.

In the drawings like reference numerals indicate like parts.

The invention as shown here is applied to an automobile trailer truck used as a refrigerator car, and is also intended to be applied to refrigerator cars such as are ordinarily used in railroad transportation.

55 In the drawings reference numeral 1 indicates the car body having a metal floor 2 supported on wooden stringers 3 which run the length of the

floor, or the length of the car body. Interposed between the floor and the wooden stringers are the channels 4, which are electrically welded to the bottom of the floor. These channels are about six inches long, and are spaced apart about 5 three feet between centers. Below the stringers 3 is placed the metal sub-floor 5, and below the metal floor is placed a series of cross-channels 6, which are spaced about two feet between centers. These channels run clear across the car body, and 10 in turn rest upon the I-beams 7, 7 which constitutes the frame that supports the car body.

The space between the metal floor 2 and the sub-floor 5 is filled with strips of cork insulation 8, which strips are cut to fit between wooden 15 stringers 3. Each of the channels 4 is perforated to receive a bolt 9, which runs horizontally through the channel 4 and the stringer 3 and fastens these two parts firmly together. The stringer 3 is cut away to form a pocket as indicated at 10, which pocket received the head of the bolt 11. This bolt passes through the stringer and through the sub-floor 5 and through the flange of one of the cross-channels, and is fastened in place by the nut 12 and washer 13. This 20 bolt firmly ties the stringer and the sub-floor and the cross-channel together. The pocket 10 is deep enough so that the head of the bolt will not make contact with the channel 4, and in this way heat leakage through the metal floor 2, the channel 4, and the bolt 11 is prevented. It will 25 also be understood that the channel 4 is insulated from the metal sub-floor 5 by the wooden stringer 3.

On each side of the car resting on the sub-floor 5a is provided a wooden nailing strip 15 which runs the length of the car except where it is broken by the upright angles 16 and 17, which are shown in horizontal section in Figure 7 and in dotted lines in Figure 4. These uprights 40 are riveted to the ends of the cross channels 6, as are indicated by the rivets 18 and 19 in dotted lines which pertain to the uprights 16, and the rivets 20 and 21 which pertain to the uprights 17.

The inside sheet 22 of the car is riveted to the angles 17, and the outside sheet 23 is riveted to the angles 16. Between the sheets 22 and 23 a space is provided which is filled with a continuous layer of insulating material 24, which runs the length of the car body. This insulating 50 material is contained in a bag which is bent to the shape shown in Figure 4. It is held in place at the bottom by a nailing strip 25, and is held in place at the top by a nailing strip 26. The insulating material preferred is the so-called 55

"Dry Zero" material which is commonly used in refrigerator car construction. The nailing strip 25 is nailed to the nailing strip 15, and the nailing strip 26 is nailed to the wooden top side plate 5 27 shown at the upper left hand corner of Figure 4.

As shown at the lower left hand corner of Figure 4, an angle 30 is provided which runs the length of the car and is the bottom side sill of 10 the car. The upright angles 16 are offset at the bottom, as indicated in Figure 4, and are fastened to the upright member of the metal angle 30. The upright member 17 is riveted directly to the web of the channel 6.

15 The nailing strip 15 is fastened by a bolt 31, which passes through the nailing strip, and through the sub-floor 5a, and the upper flange of the channel 6 and is clamped in place by the washer 33 and the nut 32. The strip is cut away 20 to form an air pocket as indicated at 35, which pocket receives the head of the bolt 31.

On the outside of the car at the bottom is riveted the rub rail 34, which is U-shaped.

The outside plate 23 is fastened to the top side 25 plate 27 by a bolt 35a, and the inside plate 22 is fastened to the side plate 27 by the bolt 36. The side plate is cut away to form air pockets in which the heads of each of these bolts are received. The bolt 36 passes through the reinforcing angle 30 37, which runs the length of the car on the inside at the top. The upper ends of the angles 16 and 17 are cut away on a taper, as shown in dotted lines, and these ends nest into tapered pockets which are cut into the wooden top side plate 27. 35 As these angles 16 and 17 are riveted to the side sheets 22 and 23, it will be seen that the side sheets, and the upright angles 16 and 17, and the top side plate 27, and the cross channel 6, and the metal angle 30 are all securely tied together. 40 On the outside at the top, an angle 38 is riveted, the upper flange of which slopes down and out. This angle runs the length of the car and the ends thereof extend half way around the ends of the car. The ends of the two angles are 45 welded together and the angles thus form a rectangular frame that encircles the car. On top of the angles 37 and 38, and the wooden top side plate 27 is supported the roof of the car, which is made up as follows.

50 A top roof plate 40 is provided, which extends the full length of the car and the full width of the car, and the sides of which are bent down on a curve as indicated at 41. To the bottom edges of the roof on the outside are riveted the angles 55 42, which run the full length of the car and half way around the end of the car. The two angles 42 are welded together at the ends, so that the two angles make a rectangular frame which encircles the car.

60 The ends of the top roof plate are bent down on the same curve as indicated at 41, and to make a rounded corner each corner is cut away with a V-shaped notch and the end and side edges after being bent to shape are suitably welded together 65 along the edges of the notches, one notch being cut in each corner to make the four rounded corners on the roof.

The inside sheet 22 of the car is reinforced by the horizontal stiffeners 46, which are made of 70 sheet aluminum bent to U-shape with suitable flanges by which they can be riveted to the sides of the car. In this way the inside sheet of the car is stiffened vertically by the upright angle 17, but is also stiffened longitudinally by the horizontal 75 stiffeners or angles 46, as above described.

The inside sheets can, therefore, resist any hammering effect due to the shifting of the load inside of the car.

A ceiling plate 43 is provided which runs the length of the car, and the side edges of which are 5 fastened to the angle 31. On top of the ceiling plate 43 are the cross angles or carline 44 and 45, the even numbers of which are fastened to the angles 31 and ceiling 43, and the odd numbers of which are fastened to the roof 40 of the car, and 10 the ends of them are cut away and are bent down and are fastened to the angle 42.

On the inside of the car at the end is placed the ice bunker 50, which is provided with one or more frames of grate bars 51, by which the ice 15 is held in the bottom of the bunker. A sheet metal plate 52, preferably of galvanized iron, encircles three of the upright sides of the bunker. The fourth side is enclosed by the wire netting 53.

For the purpose of regulating the circulation of 20 air inside the car, I provide as follows:—

As shown in Fig. 6, the air is taken in at the forward end of the car thru a ventilator 60, and if the outside air is warm this air must pass down thru the ice bunker 50, and at the bottom 25 of the bunker is driven out thru the car by an electric fan 61. If it is desired to change the air, for any reason, the air can pass out thru the ventilator 62 in the roof of the car at the tail end. At the top of the ice bunker on the inside 30 of the car, I provide a damper or valve 63, which consists of a stationary plate 64 having a series of oblong holes therein and a sliding plate 65 having a similar series of holes therein. This sliding plate 65 slides in guides 66 and 67 and this 35 plate can be moved so as to bring the holes therein into register with the holes in the stationary plate 64, in which case the air will pass thru the damper or the plate can be moved so as to put the holes in the two plates out of register with each 40 other in which case the passage of air, therethru, will be prevented. If the damper is closed then the air will pass as indicated in Fig. 6. If the damper 65 is open, the ventilators 60 and 62 will be closed and the fan will then circulate the air 45 along the bottom of the car drawing the air down thru the ice bunker causing the warm air to rise and pass to the ice bunker which it enters at the top thru the damper. This assumes that the 50 bunker is full of ice and that the car is being used in warm weather to keep the perishable contents thereof under refrigeration. A bolt 75 is provided by which the sliding plate 65 is moved or clamped in place.

If the car is used in cold weather ice will be 55 omitted from the bunker and at such time it will be necessary to artificially heat the inside of the car so to keep the perishable products thereof from freezing. For this purpose, I provide a heating apparatus 70, under the grate bars of 60 the ice bunker. This may be of any suitable type but I prefer the so-called Tropic-Air heater, which is a standard make and is regularly used for heating automobiles. This heater gets its 65 heat from the hot water that is circulated from the engine jacket and is used to heat the inside of the car. I may also use a so-called charcoal heater instead of the hot water radiator heated from the engine jacket, or the car may be heated 70 by the exhaust from the engine. In either case, the hot air will be blown out by the electric fan 61, to the bottom of the car and the cold air will descend to the ice bunker in which there will be no ice. It will be understood that the heating 75

effect will be sufficient to keep the contents of the car from freezing by a small margin.

5 I have found that by the forced circulation either when the car is under refrigeration or is being artificially heated, the difference between the temperature of the floor and ceiling of the car is kept within a very few degrees.

It will also be understood that the floor and sides of the car are water tight so that water 10 cannot leak thru them into the insulating material and when the car is unloaded it can be washed out and cleaned very effectively so that the next load that is placed in the car will not be contaminated in any way by any odor or waste 15 left in the car by the previous load.

It will be understood that all or nearly all the metal parts above described will be made of aluminum for the purpose of reducing the weight of the car body and for the purpose of avoiding rust. 20 This includes such parts as the cross channels, the subfloor and the top floor, the channels on top of the stringers, the inside and outside wall plates or sheets, and the ceiling and roof of the car, angles, etc.

25 I claim:

1. In a car the combination of a floor, cross channels under the floor, upright angles fastened to said cross channels, and inside and outside wall plates fastened to said upright angles, the odd 30 numbered angles being fastened to the inside wall member and the even numbered angles being fastened to the outside wall member, each angle being separated from the opposite wall member by an air space means for supporting the inner 35 and outer side wall plates against movement to and from one another the upright angles being longitudinally spaced by the channels, the odd numbered angles being staggered or offset relative to the even numbered angles.

40 2. In a car the combination of a floor, cross channels under the floor, upright angles fastened to said cross channels, inside and outside wall plates fastened to said upright angles, the odd numbered angles being fastened to the inside wall 45 member and the even numbered angles being fastened to the outside wall member, each angle being separated from the opposite wall member by an air space, and wooden strips running lengthwise of the car at the top and bottom of the 50 wall and between the wall members, said strips being recessed to receive the angles, means for supporting the inner and outer side wall plates against movement to and from one another the upright angles being longitudinally spaced by the 55 channels, the odd numbered angles being staggered or offset relative to the even numbered angles.

3. In a car the combination of a floor, cross channels under the floor, upright angles fastened 60 to said cross channels, inside and outside wall plates fastened to said upright angles, the odd

numbered angles being fastened to the inside wall member and the even numbered angles being fastened to the outside wall member, each angle being separated from the opposite wall member by an air space, wooden strips running lengthwise of the car at the top and bottom of the wall and between the wall members, said strips being recessed to receive the angles, and nailing strips running parallel to the wooden strips between which nailing strips and the wooden strips the 10 heat insulating material is held in place means for supporting the inner and outer side wall plates against movement to and from one another the upright angles being longitudinally spaced by the channels, the odd numbered angles being staggered or offset relative to the even numbered angles. 15

4. In a car the combination of a floor, cross channels under the floor, upright angles fastened to said cross channels, inside and outside wall plates fastened to said upright angles, the odd numbered angles being fastened to said inside wall member and the even numbered angles being fastened to the outside wall member, each angle being separated from the opposite wall 20 member by an air space, and wooden strips running lengthwise of the car at the top and bottom of the wall and between the wall members, said strips being recessed to receive the angles, the upper strip serving to hold the wall members apart the upright angles being longitudinally spaced by the channels, the odd numbered angles being staggered or offset relative to the even numbered angles. 25

5. In the side wall of a car the combination of a wooden top side plate, an inside metal plate and an outside metal plate, and bolts for fastening said metal plates to the top side plate, each of said bolts fastening but one metal plate to the top side plate and being insulated from the other metal plate said bolts being parallel to each other. 30

6. In the side wall of a car the combination of inside and outside wall plates, upright angles fastened to said wall plates, the odd numbered angles being fastened to said inside wall plate and the even numbered angles being fastened to the outside wall plates each angle being separated from the opposite wall member by an air space, and wooden strips running lengthwise of the car at the 40 top and bottom of the wall, said strips being recessed to receive the upright angles and hold them apart from each other and from the plate opposite thereto. 45

7. In a car the combination of a roof and a side wall for supporting the roof, said side wall having a wooden side plate at the top thereof, a nailing strip in the roof, and insulating material in the roof and held in place between the nailing strip and the side plate in the side wall. 50

55 RAYMOND S. HUMBURCH.
